UNITED STATES PATENT OFFICE.

HUGO M. DANKER, OF AUSTIN, ILLINOIS, ASSIGNOR OF ONE-HALF TO GERWIG & IDEN COMPANY, OF CHICAGO, ILLINOIS, A CORPORATION OF ILLINOIS.

REEL.

No. 908,559.

Specification of Letters Patent.

Patented Jan. 12, 1909.

Application filed May 9, 1908. Serial No. 431,764.

To all whom it may concern:

Be it known that I, HUGO M. DANKER, a citizen of the United States, residing at Austin, in the county of Cook and State of Illinois, have invented certain new and useful Improvements in Reels, of which the following is a description.

My invention belongs to that class of devices known as reels adapted to contain cordage, wire or any other article applicable for the same. It more particularly relates to the core which is positioned within the coil, cordage or wire. The coil, cordage or wire instead of being wound on a wooden, paper or equivalent core at the factory, is shipped without a core thus saving the consumer the cost of cordage or other material equivalent to the weight of the core, as well as freight on the core. When it is desired to place the coil on a reel or the like, it is necessary to force the core or the equivalent through the coil, an operation which is sometimes difficult owing to the flattening of the coil and the consequent disarrangement of the coil at the opening therethrough.

My improved reel and core give a very satisfactory construction for coils of the kind described.

To this end my invention consists in the novel construction, arrangement and combination of parts herein shown and described and more particularly pointed out in the claims.

In the drawings wherein like references characters indicate like or corresponding parts, Figure 1 is a perspective view of a coil of cordage, Fig. 2 is a longitudinal sectional view of a reel and core with the coil positioned thereon, Fig. 3 is an end elevation of the same, Fig. 4 is a sectional view of one end of the core and portion of the reel shown in Fig. 2, Fig. 5 is a sectional view of one end of the core with the removable end in operative position, Fig. 6 is a sectional view of a slightly modified form of core and removable end, and Fig. 7 is a sectional view of another slightly modified form.

Referring to the drawings, 1 is the coil and 2 a core therefor. The preferred form of reel for supporting the core is clearly shown in Fig. 2, in which the core 2 is arranged on a tube 5 preferably removable ends 6 and 7 of any suitable form being positioned at the ends of the core. As shown the removable ends are made in the form of

cross bars, it being obvious that they may be of any other form arranged in any other suitable way. The end 6 is provided with a collar 8 and preferably secured to the tube 5 by means of a lock or set screw 9 or its equivalent. The other end 7 is positioned at the opposite end of the core on the tube 5, the tube being preferably threaded and the end 7 retained on the bar by means of a suitable locking member 10 cooperating with the threads on the tube. The reel may be supported in any suitable way, as shown a supporting bar 4 is extended through the tube 5 and supported by means of a bail 17 or its equivalent. The supporting bar 4 may be prevented from becoming displaced by means of a collar 11 and set screw 11' or their equivalent arranged between the bail and tube 5.

When the coil comes from the factory it is substantially as shown in Fig. 1, the same being probably flattened to a more or less extent. Whether the coil is flattened at the opening or not it is preferable to have the core fit tightly in the opening so that it would be difficult, or impossible in most cases, to force the coil therethrough if the ends were square or substantially so. In order to facilitate the positioning of the core within the coil, I provide in the preferred construction a removable tapered end therefor. In the form shown in Figs. 2, 4 and 5. I provide a removable end 3 which is normally substantially positioned within the core as shown in Fig. 4 when the core 2 is positioned on the reel. When it is desired to insert the core in a coil or the like preparatory to placing the same on the reel, the core 2 is removed from the tube 5 by removing locking members 11, 10 and the cross bar 7. The end 3 of the core is then removed from its recess in the core and inserted therein in a reversed position or substantially as shown in Fig. 5. As shown, the core is preferably provided with a shoulder 12 within the recess for the end 3 to butt against while forcing the core through the coil. The core may be constructed in any other suitable way to permit removable end 3 to be positioned therein as shown in Fig. 5.

In the more simple form shown in Fig. 6, the removable end 3 is adapted to be positioned on the end of core 2, but is not made so as to be a part thereof when the core is on the reel. As shown in this figure the end

3 is provided with an extended portion 13 adapted to extend into the opening through the core 2 thus retaining the end in operative position.

5 Fig. 7 shows a removable end particularly adapted to be used on a paper core or the like, the end being extended as at 14 adapted to fit into a recess 15 in the core. As shown in this figure the ends 3 may be extended to 10 the opposite end of the core as at 16, to take a strain off the core while forcing the same through the coil.

Having thus described my invention it is 15 obvious that the core and its removable end may be made of any suitable material or reinforced in any preferred way and that various immaterial modifications may be made in the form or design shown or that the same 20 may be applicable to other styles of reels and material mentioned, hence I do not wish to be understood as limiting myself to the exact construction, arrangement and combination of parts shown and described.

What I claim as new and desire to secure by Letters Patent is:

25 1. In a device of the kind described and in combination a core and a removable substantially tapered end therefor, said core provided with a recess therein at one end thereof adapted to receive either end of said removable member.

2. In a device of the kind described and in combination, a core and a removable substantially tapered end therefor, said core provided with a recess therein at one end 35 thereof and with a shoulder within said recess, and adapted to receive either end of said removable member.

3. In testimony whereof, I have hereunto signed my name in the presence of two sub- 40 scribing witnesses.

HUGO M. DANKER.
